3 Claims. (Cl. 250—27.5)

1

This invention relates to electronic devices, and more particularly to controllable electron discharge devices suitable for amplifiers, oscillators, and the like.

In the usual type of controllable electron discharge tubes, such as exemplified by the ordinary and well known triode, electrons are attracted to the grid whenever it assumes a positive potential with respect to the cathode; and the resultant grid current imposes limitations upon the efficient and effective use of such tubes in various applications. In power amplifiers and oscillators, for example, the grid current flowing during the time the grid is positive represents a substantial part of the electron space current and is a wasteful power loss. In voltage amplifiers and similar applications of the conventional triode, where it is desired to have the output vary within close limits with the variations of the input voltage impressed on the grid, the flow of grid current when the grid assumes a positive potential tends to modify the potential on the grid and cause distortion of the output. Also, in various applications of the usual triode, the grid current existing while the grid is positive has a tendency to overheat the grid and cause undesirable thermionic or secondary emission of electrons from the grid, particularly where thoriated tungsten or oxide coated cathodes are used in the interests of emission efficiency and the grid may accumulate a deposit of emissive material evaporated or sputtered from the cathode. These and other limitations in the efficiency and use of the usual type of grid controlled electron discharge tube are due primarily to the attraction of electrons to the grid when it assumes positive potential with respect to the cathode; and these limitations can be mitigated and in many respects entirely overcome and the efficiency and utility of such tubes clearly increased, if the flow of electrons to the positive grid can be effectively prevented.

With these considerations in mind, one of the objects of the present invention is to provide a controllable electron discharge device which may be proportioned to have the desirable operating characteristics of the usual grid control triode or similar multiple electrode tube, but which does not have any appreciable electron current to the grid or control electrode, even when this grid or control electrode assumes relatively high positive potentials with respect to the cathode.

A further object of the invention is to attain this desirable objective by a simple and effective structural organization, in which the component

2

parts may be readily proportioned and arranged to obtain any desired rating and operating characteristics.

Various other objects, attributes and characteristic features of the invention will be in part apparent, and in part pointed out, as the nature of the invention and certain specific embodiments are hereinafter described.

Generally speaking, and without attempting to define the nature and scope of the invention, it is proposed to combine a magnetic field with a cathode, anode, and a control electrode in such a way that, although the control electrode may perform its usual function of controlling the electron space current in accordance with variations in its impressed potential, the electrons emitted by the cathode and forming the electron or space current are influenced by the magnetic field so as not to reach the control electrode or grid, even though it assumes a relatively high positive potential with respect to the cathode in the operation of the tube.

Considering the general attributes of the invention from another viewpoint, the control element or electrode, instead of being the conventional grid with spaces between its wires for the passage of electrons, and located between the cathode and anode in the path of direct movement of electrons from the cathode to the anode, is disposed to one side of the direct or normal path of electrons emitted by the cathode and attracted to the anode, but in such a position that variations in the electrostatic field due to potentials on the control electrode may influence the intensity of the electron current and exercise the same controlling function as the grid of the conventional triode; and this arrangement or disposition of cathode, anode and control electrode is supplemented by a magnetic field acting in a direction and with such intensity as to confine the movement of electrons emitted from the cathode into a beam or stream over a discharge path of the appropriate area which does not touch the control electrode even though it assumes a relatively high positive potential with respect to the cathode.

These and other structural characteristic and operating features of the invention will be discussed more in detail in describing certain physical embodiments of the invention.

Although the structural organization and arrangement of parts embodying the invention may assume a wide variety of forms, and the invention is in no way limited to any one specific construction or arrangement of parts, it is expedient

ent, in explaining the nature and attributes of the invention, to refer to the specific embodiments of the invention illustrated in the accompanying drawings in a schematic and diagrammatic manner, the parts being shown in these drawings more with a view of facilitating an explanation and understanding of the invention than for the purpose of illustrating the details of any particular construction and arrangement of parts that may be advantageously employed in practice.

In the accompanying drawings,

Fig. 1 is a general view, partly in section and partly in perspective, of one elemental form of controllable electron discharge tube embodying the invention;

Fig. 2 is a diagrammatic representation of the relationship and function of the component elements of the tube of Fig. 1, with a schematic representation of associated circuit connections;

Fig. 3 illustrates diagrammatically a variation in the disposition of the elements of the tube of Fig. 1 in connection with a magnetic field provided by a permanent magnet; and

Figs. 4 and 5 illustrate, for explanatory purposes, typical curves of the operating characteristics of one form of tube embodying the invention.

Considering first the structural organization of what may be said to be an elemental form of an electron discharge tube of this invention as shown in Fig. 1, this tube comprises a thermionic emissive cathode C of the filamentary type, which may be a directly heated wire of tungsten or other emissive metal, a wire thoriated or oxide coated, or a cathode of the oxide coated indirectly heated type, the particular type of the cathode not being material to the present invention.

The cathode shown is assumed to be a nickel core wire spirally wound with a fine nickel wire to aid adherence of the emissive coating and to help in maintaining a uniform temperature.

In the interests of efficiency of low operating temperature, it is considered preferable for ordinary applications to employ an oxide coated cathode formed and treated in the manner disclosed in the prior patents to D. V. Edwards, et al., No. 1,985,855, December 25, 1934, and No. 2,081,864, May 25, 1937, because it is found that such a cathode has superior qualities in the way of life and durability, as well as high emissivity at relatively low temperatures.

In the simplified arrangement illustrated, this cathode C is welded or otherwise suitably attached at its ends to non-emissive supports 5, 6 sealed in the reentrant stem or press 7 of the glass envelope E for the tube, said supports 5, 6 being connected by leads in the usual way to pins 8, 9 of a base 10 cemented to the glass envelope in accordance with the usual practice.

In the elemental type of tube shown in Fig. 1, the anode comprises two like flat plates A, A¹ located on opposite sides of the cathode C in planes substantially parallel to the linear axis of the cathode, with the edges of said plates parallel with the cathode at substantially equal distances from the cathode. As shown in Fig. 1, these anode plates A, A¹ are located parallel with each other above and below the cathode C at equal distances in conformity with the desired voltage and current characteristics of the tube.

In the simplified construction illustrated, the two anode plates A and A¹ are electrically connected and held in the proper relative positions by a support or brace 11 welded to these plates,

and the upper anode plate A is supported by a rigid support 12 extending through a seal 13 in the upper end of the envelope E and connected to a terminal cap 14 in accordance with the usual practice. These anode plates A, A¹ are preferably formed from sheet stock of the appropriate thickness for stiffness or rigidity, with stiffening flanges or ribs (not shown) if desired, of tantalum, or a like non-magnetic material capable of operating at a high temperature with low emissivity and having characteristics suitable for the plates of electron discharge tubes.

In the elemental tube shown in Fig. 1, the control electrode, having the function of the grid in the conventional triode, comprises two like flat plates G, G¹ located parallel to each other on opposite sides of the cathode C substantially parallel with the cathode and in planes substantially parallel with the straight line between the anode plates A, A¹ through the cathode, which may be considered to be the axis of the tube.

As shown, these control electrodes G, G¹ which may conveniently be termed grids, are assumed to be in the form of flat sheets of tantalum, or a like non-magnetic material, without any grid wires or openings characteristic of the usual grid structure employed in electron discharge tubes, although it should be understood that these control electrodes may be plates with openings therein, or some form of a reticulate or striated structure, although such openings are not necessary for the passage of electrons as in the conventional grid.

In the simplified structure illustrated in Fig. 1, the control electrodes or grids G, G² are electrically connected and supported in the desired relationship by a cross support or brace 15 welded thereto; and this brace is welded to a support 16 sealed in the reentrant stem 7 of the envelope E and connected to a pin 17 on the base 10 in accordance with the usual practice.

In addition to the electrodes in an evacuated envelope as described, the electron discharge tube of this invention further includes suitable means for providing a steady magnetic field of the appropriate strength directed in a proper direction with respect to the electrodes to influence the movement of the electrons in a way to prevent them reaching the control electrodes. In the simplified form of the elemental tube shown in Fig. 1, this magnetic field is assumed to be provided by a coil or solenoid M energized with unidirectional current, as indicated by the arrows and symbols (+) and (-). This magnetostatic field is directed along the axis of the tube substantially at right angles to the surfaces of the anode plates A, A¹ and parallel to the surfaces of the control electrodes G, G¹, as indicated by the arrow H, so that the magnetic lines of force act along the straight and normal path for movement of electrons from the cathode C to the anodes A, A¹.

Fig. 3 illustrates schematically a modified organization in which the filamentary cathode C is disposed vertically in the tube envelope E, shown broken away and partially in section, with the anode plates A, A¹ disposed vertically on opposite sides of the cathode, and the control electrode plates G, G¹ disposed vertically on opposite sides of the cathode in planes substantially at right angles to the planes of the anodes. In this form of the invention, the steady magnetic field is illustrated as provided by a permanent magnet PM of any one of the well-known permanent magnet materials, preferably an alloy of

iron, nickel and aluminum, commonly known as Alnico. This permanent magnet PM is positioned as indicated diagrammatically in Fig. 3 to provide magnetic lines of force in the direction indicated by the arrow H substantially at right angles to the planes of the anodes A, A¹ and parallel to the surfaces of the control electrodes G, G¹. This permanent magnet PM is preferably provided with soft iron pole pieces 48 to give a more effective flux distribution.

Since the total anode current depends upon the area of the anode surface, as well as the cathode to anode distance and the effective anode voltage, it is contemplated that the effective area of the anode may be increased to obtain desired current readings by elongation of the anode plates A, A¹ in Figs. 1 and 3, in a direction parallel to the filament axis which have their width determined by the spacing of the control electrodes G, G¹ selected for the desired control characteristics. Also, it is contemplated that a plurality of elemental tube units, such as shown in Figs. 1 and 3 may be assembled in the same envelope and have their anodes and control electrodes interconnected, or employ anodes and control electrodes common to adjacent units, by any suitable disposition or relationship of the parts adaptable for effectual mounting and support of the electrodes in the tube envelope. Various arrangements of expanding the surface area of the electrodes of the elemental tube unit, or packing a plurality of tube elements in some cellular-like organization in the same envelope may be employed without departing from the fundamental attributes and advantages of this invention.

The particular organizations illustrated in Figs. 1 and 3 are merely typical of the various other geometrical arrangements and disposition of the cathode, anode and control electrode, together with means providing a magnetic field characteristic of this invention; and it is contemplated that these organizations illustrated may be modified and adapted in other ways, in addition to varying the space relation and dimensions of the parts, as may be expedient to obtain tubes having different voltage and current ratings and operating characteristics.

After the tube elements have been mounted in the envelope, which is provided with the usual exhaust tube, the electrodes, supporting elements and envelope are freed of occluded gases by a suitable baking, induction heating and bombardment procedure; and the envelope is thoroughly evacuated of all air and gases, in accordance with recognized practice to provide what is known as a "hard" tube.

Considering now the function and operation of the controllable electron discharge tube of this invention, it is found that a disposition of electrodes, together with a magnetic field, such as illustrated and described, provides a control of the electron or space current to the anodes in accordance with the variations in the potential of the control electrodes with respect to the cathode, and that there is no appreciable movement of electrons to the control electrodes and a resultant electron current, even though the control electrodes assume a relatively high positive potential with respect to the cathode. Theoretical consideration indicates that this action or performance of the device of this invention may be attributed to certain recognized phenomena in connection with the emission and movement of electrons in discharge tubes and in

magnetic fields; but it should be understood that the following discussion of a theory of operation is not comprehensive, nor necessarily applicable in all details to the various forms which the tube of this invention may take.

With regard to the controlling effect of the potential on the control electrodes, it may be said that the number of electrons emitted from the cathode and attracted to the anodes in an electron discharge tube is dependent upon the potential gradient to the cathode, and primarily the electrostatic field adjacent the cathode. In the tube of this invention, the electrostatic field of the existing potential on the control electrodes 10 acts to modify this potential gradient provided by the space charge and anode voltage in such a way as to control the electron current actually flowing to the anodes and through the external output circuit. It may be assumed that the control electrodes of the tube of this invention act in this respect much like the grid of the conventional triode, negative potentials tending to reduce and cut off electron current to the anodes, and positive potentials acting to neutralize the effect of the space charge and also supplement the anode potentials tending to draw electrons from the cathode. In this connection, the relative spacing of the elements as well as the voltages involved, are factors in determining the intensity of the anode current and the effectiveness and range of control of the potentials on the control electrodes.

Speaking generally, it is contemplated for ordinary uses of the tube that the cathode will be capable of emitting a surplus of electrons at the maximum anode operating voltage, so that the anode current is limited by space charge effects. Under such conditions, the anode current for a given anode voltage increases with a decrease in anode to cathode spacing; and in general the anode to cathode spacing may be chosen for certain anode voltages to provide the desired anode current.

With respect to the dimensions and space relation of the control electrodes, the effective area of the control electrodes and their distance from the cathode depending in general upon the control potentials to be used for the control electrodes, amplification factor, and control characteristics desired, since it may be considered that the control exercised by the grid is dependent in general upon the potential of the electrostatic field created adjacent the cathode emitting surface by the combined action of the potentials on the control electrodes G, G¹ and on the anode plates A, A¹. When the control electrodes G, G¹ are spaced closer to the cathode C than the anodes A, A¹, as shown in Fig. 2, in general there is an increase in the ratio of the effectiveness of the control electrode and anode voltages in producing an electrostatic field near the cathode; and while such relative spacing is generally favorable for many applications where a range of control voltages lower than the anode voltage are desirable, it should be understood that other relative spacings of the control electrodes and the anode plates with respect to the cathode may be employed without departing from the invention. Similarly, the control electrodes G, G¹, indicated in Fig. 2 as extending most of the distance between the anode plates A and A¹, may extend over any desired part of this distance, dependent upon the control characteristics desired; or even project beyond the anode plates if desired for structural purposes. In short, the dimensions

and relationship of the tube elements indicated in the accompanying drawings are merely typical and may be materially changed without departing from the functions and mode of operation characterizing this invention.

Investigations indicate that the operating characteristics of the tubes of this invention are dependent upon the proportioning and spacing of the tube elements in much the same way as in the conventional triode or similar multiple electrode tube, in accordance with well-known principles relating to space charge effects, potential gradients, electrostatic fields of applied potentials, and the like. Since these principles and empirical data in this respect are well known in connection with the usual type of electron discharge tube, no attempt will be made to discuss in detail to effect of changing the relative proportions and spacing of the tube elements. Generally speaking, the cathode and anode spacing determines the space charge effect, and the proximity of the control electrodes to the cathode, as well as their area and potential as compared with the anodes, determines the effectiveness of variations in potentials on the control electrode upon the flow of anode current. Theoretical considerations, as well as investigations, indicate that various parts may be proportioned and spaced and a tube geometry selected to obtain a wide variety of operating characteristics.

Considering now the important feature of this invention of utilizing the magnetic field in a way to minimize or eliminate electron current to the control electrodes at positive potentials, it is a familiar phenomena that a magnetic field will influence the path of movement of an electron.

More specifically, an electron as a negatively charged particle while moving in a magnetic field is acted upon by a force which is perpendicular to the direction of movement of the electron as of a given instant and also perpendicular to the direction of the magnetic field. This force is dependent upon the strength of the magnetic field, and also upon the component of the instantaneous velocity of the electron which is perpendicular to the direction of the magnetic lines of force. In this respect an electron in motion in a magnetic field may be said to be subjected to forces similar to those acting on a current carrying conductor moving in a magnetic field; and the same quantitative relations apply. While an electric field, such as produced by voltages on electrodes in the tube, exerts a force on an electron whether at rest or in motion, and in the direction of the field, a magnetic field exerts force on an electron only when it is in motion, and in a direction at right angles to the direction of such magnetic field. Consequently, a magnetic field does not accelerate or retard the motion of an electron under the influence of an electric field, but merely changes its direction of movement.

Referring to the diagrammatic illustration in Fig. 2, and assuming the magnetic field acts either up or down in the direction indicated by the arrow H along the axis of the tube extending through the cathode and parallel with an imaginary line indicated by the dash lines E , it can be seen that electrons leaving the surface of the cathode with an initial velocity either up or down towards an anode plate A or A^1 and in the same direction as the magnetic lines of force, are not effected by the magnetic field and move in straight lines toward such anode under the in-

fluence of the electric field of the anode voltage. In the case of electrons leaving the surface of the cathode with a component of velocity at right angles to the magnetic lines of force, however, such electrons will be deflected by the magnetic field in accordance with well known principles; and since these electrons are subject to the influence of the electric field as well as the magnetic field, they will move in what may be called a spiral path toward one of the anodes. In other words, it may be said that the magnetic field acts to converge or focus the electrons leaving the cathode into a beam or stream directed toward each of the anodes, as indicated by the dotted lines in Fig. 2.

Generally speaking, the path of movement of the electrons emitted from the cathode is dependent upon their velocity and the intensity of the magnetic lines of force; and the tube elements 20 may be arranged and proportioned, and anode voltages and magnetic field strength chosen or selected, such that the forces acting on the electrons to confine them into a prescribed beam, as compared with the forces exerted on the electrons by positive potentials on control electrodes, will cause all or substantially all of the electrons emitted from the cathode to be focused into a discharge path to the anodes and escape the control electrodes. In other words, the strength of 25 the magnetic lines of force, in connection with the proportioning and spacing of the electrodes and voltages employed, may be such that there is no appreciable electron current to the control electrode, even though said control electrode assumes a high positive potential with respect to the cathode.

Since the tube of this invention involves the influence of a magnetic field upon the electrons moving from the cathode to the anode, it is desirable 40 to avoid any weakening or distortion of this magnetic field by employing non-magnetic metals for the electrodes and many of the supporting elements. For ordinary purposes it is considered 45 preferable to employ tantalum for the electrodes, on account of the facility with which this metal gives up occluded gases and its tendency to absorb gases given off during operation. Molybdenum, or other non-magnetic metals of similar characteristics, are preferably employed 50 for the mounting and supporting elements of the tube, except at the glass seals, rather than nickel, commonly employed for such purpose, in order that the magnetic qualities of nickel may not adversely affect the magnetic flux distribution.

To illustrate this characteristic of the tube of this invention, as compared with the conventional triode, Fig. 4 shows curves of anode current plotted 55 against anode voltage for different control element potentials per unit of cathode length for a typical tube of this invention; and Fig. 5 illustrates similar curves of anode current against control element potential for different anode voltages of another typical tube. It should be understood that these curves are merely representative of one specific form of a tube, but they serve to illustrate how this invention provides a tube in which the control may be provided by positive 60 control element potentials without any appreciable or readily measurable electron current to the control electrode.

Referring to curves of Fig. 4 for the particular tube under consideration, it will be noted that 75 there is no appreciable anode current for a zero

potential on the control electrode until the anode has a voltage of some 500 volts, and that the increase in anode current for increases in anode voltage is very slight.

As indicated by the curves of Fig. 5, this particular organization gives an electron discharge tube controlled in effect primarily by positive potentials of the control electrode thereby showing a marked contrast with the conventional triode. In this connection, it should be understood that for the conditions of voltage and current shown in Figs. 4 and 5 there is no readily measurable electron current to the control electrode.

The characteristic curves of Figs. 4 and 5 are merely typical or representative of one specific organization of the invention, and it should be understood that the dimensions and spacing of the electrodes may be varied and chosen to give quite different operating characteristics.

From this illustration and explanation of specific embodiments of the invention, it can be seen that a magnetic field may be combined with a disposition of electrodes, constituting a thermionic cathode, anode and a control electrode, and included in an evacuated envelope, in such a way that the anode current may be effectively controlled in accordance with potentials on the control electrode, without having any substantial or objectionable electron current to the control electrode when it assumes positive potentials with respect to the cathode. A controllable electron discharge tube of this type, characterized by the absence of any electron current to the control electrode when positive, may be advantageously employed in various applications, where the conventional triode or similar multiple electrode tube is used, more particularly in power amplifiers and oscillators, where the grid current existing with positive grid potentials and characteristic of the ordinary triode, is a limitation upon efficiency and performance. Aside from indicating schematically in Fig. 2 typical connections for input and output circuits for the tube of this invention, no attempt has been made to illustrate the circuits for applying a tube of this invention to the field of amplifiers and oscillators, since the tube of this invention is applicable to any one of the various types of circuit organizations, commonly used with triodes for such purposes. In short, a tube of this invention, which may be termed a magna-triode, is in effect an improved or equivalent form of the well known conventional triode, and in general is applicable to all the uses to which such triodes are now applied.

In the particular embodiments of the invention illustrated and described, a filamentary type of cathode has been assumed, and since such a cathode provides electron emission in all directions from its axis, it is considered expedient to provide anodes on opposite sides of such cathode, and similarly two control electrodes. It should be understood, however, that this is merely a typical or illustrative organization, and that the same principles and mode of operation characterizing the invention may be applied to other forms of cathodes, number and arrangement of electrodes. Similarly, while the anodes have been illustrated as flat plates, it should be understood that these anodes may have curved surfaces, as may be best adapted to the operating characteristics of the tube desired.

The current for energizing the coils shown in

Figs. 1 and 2 for providing the magnetic field characteristic of this invention may be derived from any suitable source; and on account of the power requirements for such an electro-magnetic field, it is desirable to use permanent magnets to provide this magnetic field when the current and voltage ratings of the tube, or other operating characteristics, permit permanent magnets to be used effectively within the space limitations desired. The term magnet is used for convenience in the claims as a generic expression to include a permanent magnet, a solenoid, or any other type of like device which constitutes a source of magneto-motive-force.

Various adaptations, modifications, and additions may be made to the specific embodiments of the invention illustrated and described without departing from its underlying principles, functions, and mode of operation; and I desire to have it understood that the invention is not limited to the specific structural organizations illustrated or described, but may take a wide variety of other forms.

What I claim is:

1. A controllable electron discharge tube comprising, an evacuated envelope, a straight filamentary thermionic emissive cathode in said envelope, supporting elements sealed in said envelope for supporting said cathode at its ends and supplying heating current thereto, an anode within said envelope having opposing surfaces of substantial area on opposite sides of said cathode substantially parallel with its axis, said anode surfaces being interconnected within said envelope to operate at the same potential, a pair of flat control electrodes in said envelope connected together within said envelope and disposed one on each side of said cathode in planes substantially at right angles to said anode surfaces, elements sealed in said envelope for providing separate lead-in connections for said anode and control electrodes, said anode and control electrodes being of a readily degassed but non-magnetic material, and a magnet outside of said envelope providing magnetic lines of force directed substantially at right angles to the axis of said cathode and the surfaces of said anode, said magnet providing a magnetic field strong enough to prevent significant electron current flow to said control electrodes when the positive potentials applied thereto are relatively high and have a substantial effect upon the electrostatic field at the emissive surface of the cathode and the space current drawn from said cathode.

2. A controllable electron discharge tube comprising a highly evacuated envelope, a straight filamentary thermionic emissive cathode supported at its ends by a pair of supporting elements sealed in one end of said envelope, an anode of sheet metal within the envelope having opposing surfaces on opposite sides of said cathode generally parallel with its axis and equidistant therefrom, a rigid connection within said envelope between said anode surfaces to maintain them in their space relationship and at the same operating potential, a connection for said anode sealed in the other end of said envelope, a control electrode having surfaces on opposite sides of said cathode substantially at right angles to said anode surfaces, a supporting element for said control electrode sealed in the same end of said envelope as said cathode supporting elements, said anode and control electrodes being of a non-magnetic material, and a magnet out-

11

side of said envelope providing a strong magnetic field directed transversely of said cathode and substantially at right angles to said anode surfaces, said magnetic field acting to direct electrons emitted from said cathode under the combined influence of positive potentials on said control electrode and anode along paths escaping the surface of said control electrode in spite of a relatively high positive potential applied thereto, said magnetic field cooperating with said control electrode to provide beams of space current extending to said anode surfaces of an intensity dependent primarily upon the positive potential of said control electrode and without having significant electron current flow to said control electrode.

3. A controllable electron discharge tube comprising a linear thermionic emissive cathode, an anode comprising surfaces extending throughout the length of said cathode on opposite sides thereof in planes substantially parallel with the axis of said cathode, a rigid metallic connection within said envelope between said anode surfaces to maintain them at the same operating potential, a control electrode comprising a pair of flat plates electrically connected together within said envelope and disposed one on each side of said cathode, said control electrode having its surfaces extending throughout the length

12

of the emissive surface of said cathode in planes substantially at right angles to said anode surfaces, a magnet providing a magnetic field acting in a direction substantially at right angles to the axis of said cathode and said anode surfaces, said magnetic field having a strength with relation to the spacing of said control electrodes to permit a relatively high positive potential to be applied to said control electrodes without having significant electron current flow to said control electrodes, said control electrodes and anodes being made of a readily degassed but non-magnetic material to avoid weakening or distortion of the magnetic field acting upon the electrons emitted from the cathode.
